UNITED STATES PATENT OFFICE.

MARTIN WILTON KIRKLAND, OF ABBEVILLE, ALABAMA.

CAR-COUPING.

1,027,207.

Specification of Letters Patent. Patented May 21, 1912.

Application filed July 1, 1909. Serial No. 505,348.

To all whom it may concern:

Be it known that I, MARTIN W. KIRKLAND, a citizen of the United States, and a resident of Abbeville, in the county of Henry and 5 State of Alabama, have invented a new and Improved Car-Coupler, of which the following is a full, clear, and exact description.

This invention relates to car couplers, and the object of the invention is to produce a 10 coupler of simple construction which will couple automatically when the cars are brought together, but which can be readily operated from the side of the coupler so as to disconnect the coupler when desired.

15 The invention consists in the construction and combination of parts to be more fully described hereinafter and particularly set forth in the claim.

Reference is to be had to the accompanying 20 drawings forming a part of this specification, in which similar characters of reference indicate corresponding parts in all the figures.

Figure 1 is a vertical longitudinal section 25 taken through a car coupler constructed according to my invention; Fig. 2 is a horizontal section through the coupler; and Fig. 3 is a cross section taken on the line 3-3 of Fig. 1.

30 Referring more particularly to the parts, 1, 1, represent the coupler heads which are of similar construction. Each coupler is formed with a deep mouth 2 which extends back into the interior thereof longitudinally, 35 and this mouth is formed on its forward and lower side with an inclined or curved guide lip 3. At the upper edge of this lip 3, an angular notch 4 is formed, and beyond this notch, a downwardly extending recess 40 5 is formed in the lower part of the coupler head, as indicated. Through this recess 5 a transverse pin 6 passes, which pin secures in position a link 7. The body of this link 7 is disposed in a substantially horizontal position 45 and forms a tongue projecting over the mouth of the coupler, as indicated. The rear part of the link is formed into a laterally offset shank or arm 8 which extends down into the recess 5 and is attached to the 50 pivot pin, as shown. Each tongue 7 is formed at its forward end with a bill 9, presenting an inclined or curved edge 10. At the point where the notch 4 intersects with the lip 3, a transverse edge or rest 11 is 55 formed, and this rest supports the links in a substantially horizontal position when the

cars are being brought together to couple them. As the cars come together, the edges 10 strike the lips 3 and the ends of the tongues become elevated so that the free end 60 of each tongue passes into the mouth of the opposite coupler.

On the lower edge of each tongue near its outer extremity, that is, near the bill 9, a downwardly projecting tooth 12 is formed, 65 which presents a vertical shoulder 13, and this tooth 12 drops down into the notch 4, as indicated, by the action of gravity on the links. As shown in Fig. 2, the links are disposed side by side. In this way, when the 70 cars have been coupled, two links are presented connecting the coupler heads. In order to release the links, I provide in the rear ends of the coupler heads, horizontal 75 transverse releasing shafts 14. These shafts 80 project considerably beyond the coupler heads, as shown, and are provided with handles or levers 15 which project inwardly, that is, they project toward each other. In the rear portion of each mouth 2, a dog plate 85 or dog 16 is mounted, and these dogs rest respectively upon the laterally extending hubs 17 of the links at their point of attachment to the pins 6. In this way the dogs 16 are brought directly under the projecting 90 bills 9 of the links. The dogs 16 have elongated hubs or sleeves 18 which are formed integral therewith, and the ends of these sleeves lie adjacent to the side walls of the coupler heads so as to prevent the shaft 14 95 from moving longitudinally. When it is desired to release the links, the handles or levers 15 are moved upwardly, and this raises the dogs 16 under the bills 9. The dogs engage the edges 10 of the bills and 100 raise them so as to disengage the teeth 12 from the notches 4. The cars can then be moved apart and the tongues will then descend to their normal position, being supported on the rests or edges 11. At the 105 points where the shafts 14 receive the sleeves 18, they are formed with square necks 19, as indicated in Fig. 1. This angular form of the neck prevents the dog from rotating except when the shaft rotates, and insures a rigid connection between the shaft and the dog. If the levers 15 are held up so that the dogs 16 hold the links 7 in an elevated position, the cars may be brought together without becoming coupled together. On account 110 of the arrangement of the pins 6 it will be evident that the links 7 tend by gravity to

hold their teeth 12 in engagement with the notches 4, as each link tends to swing downwardly at its free end.

Having thus described my invention I claim as new and desire to secure by Letters Patent,—

A car coupler comprising a head having a mouth provided with an inclined guide lip at the lower edge thereof and with a transverse rib at the inner edge of the guide lip, a link provided at one end with an angular portion having a bearing, a head having an opening at the rear of the guide lip for receiving the angular portion, said portion being of such length that when the link rests upon the guide lip, the said link will be in substantial horizontal position and in position for entering the mouth of the adjacent

head, a pivot pin engaging the bearing and the head to hold the link in place, said link being at one side of the head, the head having an inwardly extending stop at the opposite side for retaining the bearing of the link in position, said link having a catch extending out of the mouth, and a dog normally resting on the stop and the bearing of the link for engaging the catch of the adjacent coupler to lift the same.

In testimony whereof I have signed my name to this specification in the presence of two subscribing witnesses.

MARTIN WILTON KIRKLAND.
